(57) **CLAIM**

We claim the ornamental design for the tip of a sample holder, as shown and described.

DESCRIPTION

FIG. 1 is a perspective view of the tip of the sample holder of the invention.

FIG. 2 is a top plan view of the tip of the sample holder of FIG. 1.

FIG. 3 is a bottom view of the tip of the sample holder of FIG. 1.

FIG. 4 is a side view of the tip of the sample holder of FIG. 1.

FIG. 5 is another side view of the tip of the sample holder of FIG. 1; and,

FIG. 6 is a front view of the tip of the sample holder of FIG. 1.
